UNITED STATES PATENT OFFICE.

MAXIMILIAN WEIL, OF NEW YORK, N. Y.

ACOUSTIC APPARATUS.

Application filed May 20, 1924, Serial No. 714,574. Renewed November 12, 1928.

My present invention relates to sound reproducers and more especially to amplifying sound reproducers, and has a preferred application to phonographs in which the usual 5 horn or amplifier serves also as the horn or amplifier of a radio or telephone receiver.

It is among the objects of the invention to provide a combined apparatus which can be used at will, either as a phonograph or as a 10 radio loud speaker, without, however, involving any change or mutilation of the usual approved phonograph sound box, tone arm or amplifier, which avoids any extra drag or wear on the phonograph record even 15 though a telephone receiver element much heavier than the usual sound box is employed, and in which the sound vibrations emanating from the receiver diaphragm are efficiently amplified without loss by leakage, 20 from near the throat of the amplifier.

Another object is to provide a construction of the type mentioned in which the volume of sound emitted from the amplifier horn in radio operation, can be delicately varied 25 or adjusted at will, without manipulation of the electric control elements of the receiving set and without the loss in efficiency due to leak with respect to the phonograph tone arm.

Another object is to provide a tone modifier for a simple phonograph, or for one combined with radio appurtenances, which in 30 all settings thereof will provide a continuous conduit for sound without sharp valve elements projecting across the sound passage 35 that might impair the effectiveness of the production.

Another object is to provide a construction of the type mentioned devoid of arrangements or elements that might develop looseness or rattle, which may be incurred, for instance, in constructions embodying flap control valves or involving the substitution of a radio receiver for the sound box in changing 40 from phonograph to radio operation and vice versa.

Another object is to provide a unit or assembly simple, rugged and compact, which will enhance the attractiveness of the phonograph and which can be easily applied, without the exercise of skill to phonographs of the type now in use, in order to accomplish 45 the various objects previously noted.

In the preferred embodiment of the inven-

tion, the sound vibrations whether from the phonograph sound box or from the telephone receiver or other telephonic speaker are admitted into the small end of the amplifying horn, so that the full length of the amplifying horn is included in the acoustic circuit 55 for both phonographic and telephonic reproduction.

In a preferred embodiment, I provide a conduit which I call the radio conduit, preferably fixed with respect to the motorboard, 60 mounting a telephone receiver element at its smaller end and flaring to merge with the small end of the amplifier. Means is provided to prevent, during radio operation, any communication between the radio conduit and 65 the conduit that connects the sound box with the small end of the amplifier. For this purpose, I provide a valve, which in one setting shuts off the tone arm with respect to the amplifier throat, while affording a direct communication from the telephone receiver to said throat, and in another position affords communication between the tone arm and the amplifier throat, while preferably closing off the conduit leading from the 70 radio receiver. A rotary valve is preferred and more especially one which has intermediate settings, so that it performs in addition 75 to the functions noted, that of a tone modifier by which the volume of sound emitted from the horn can be regulated, either in phonograph or in radio operation, but preferably in both modes of use.

The radio conduit is preferably embodied 80 in a casting, the valve constituting an element in the connection from said conduit to the amplifier throat, said valve also controlling a passage of more or less uniform cross-section, which I call the phonograph conduit, 85 and which connects the mouth of the tone arm with the throat of the amplifier. In the preferred detailed construction, a unitary casting is provided which may be rectangular in external form, is secured to the motorboard and includes both the radio and 90 the phonograph conduits, cast thereinto, the former preferably of rain's-horn shape to provide considerable length in a small length of casting, the latter relatively straight. The two conduits extend preferably either diametrically opposite, or at some other angle 95 relative to each other, and provide a valve 100 casing at their junction in which is disposed 105

the rotary control valve, the latter operable by an exposed knob.

In the accompanying drawings,

Fig. 1 is a fragmentary top plan view of a phonograph embodying my invention,

Fig. 2 is an enlarged view in transverse section taken along the line 2—2 of Fig. 1,

Fig. 3 is a view in longitudinal section taken along the line 3—3 of Fig. 2.

Fig. 4 is a fragmentary view illustrating the controlling valve moved to its other extreme position,

Fig. 5 is a plan view of the handle and dial for the controlling valve,

Fig. 6 is a sectional view taken along the line 6—6 of Fig. 1,

Fig. 7 is a view similar to Fig. 1 showing the selector unit above the motorboard, and

Fig. 8 is a sectional view of one of many possible modifications.

The phonograph 10 shown of conventional construction includes a motorboard 11, above which is the usual turntable 12 (Fig. 1) that carries the disk record 13, and is rotated by a motor (not shown). In applying my invention to a machine of this general character, the motorboard is formed with a cut-away portion or opening 14 for the accommodation of a casting 15, formed with a peripheral flange 16 seating on the edges of the opening 14 and held in place by screws or similar securing devices 17, passed through lugs 18 at the ends of the flange. The exact shape of the casting 15 is, of course, subject to considerable variation, but for purposes of convenience in assembly and attractiveness in appearance, I prefer to make the body of this casting of generally rectangular shape fitting within a rectangular opening 14 in the motorboard. Aluminum is suitable for the casting, but various other materials may be substituted.

The throat 19 of the usual amplifier or horn is provided with an external flange 20 (Fig. 2) appropriately secured to the lower end of a control valve housing 21, integral with and disposed approximately centrally of the casting. Rotatably mounted in the housing 21 is a valve 22 operable to selectively place the amplifier 19 in communication with either of a pair of conduits or passage-ways 23 and 24 in the casting at opposite sides of the valve. The passage-way 24 is relatively wide and may be of substantially the same cross-sectional area throughout its length, although even along this short length, a slight taper is desirable, and when the valve is set accordingly, connects the amplifier 19 with the large end of the tone arm 25 of the phonograph. The tone arm, which may be of entirely conventional construction, carries the sound box B and is swiveled in a socket member 26 at the open end of the passage 24 which thus forms a continuation of

the sound wave channel in the tone arm. The tone arm is secured against accidental removal from the socket 26 by a stud 27 carried at the upper end of a curved arm 28 rising from and preferably integral with the socket member. This stud engages a flattened portion 29 on the upper surface of the tone arm and holds the same against accidental tilting while permitting free swinging movement thereof.

A bushing 30 secured within the inlet end of the passage-way 23 at the point where it communicates with the face of the casing 18 provides a mounting for a radio reproducer of any desired type, such for instance, as the telephone receiver 31. Preferably the receiver is formed with a depending socket member 32, encircling the projecting upper end of the bushing 30 and secured thereto by set screw 33. If it is desired to mount the telephone in concealed rather than in exposed position, it may be secured to a boss 34 integral with the casting and communicating with the neck of the passage-way 23 (Fig. 6). This boss or nipple is ordinarily closed by a plug 35 and the position of the plug 35 and bushing 30 may be reversed when it is desired to attach the telephone in a concealed position within the motor casting.

As seen most clearly in Figs. 3 and 4, the rotary valve member is formed with an opening or cut-away part 36 adapted for registration with the respective passages 23, 24 and is formed with an external groove 37 receiving a set screw 38 projecting through the valve casing, engaging with the ends of the groove to act as a stop and limit the turning movement of the valve in each direction.

The conduit connecting the telephone receiver to the amplifier throat should diverge and preferably be relatively long, so that the wave front can gradually increase from the relatively small receiver opening to the much larger amplifier throat. On the other hand, the conduit 24 connecting the mouth of the standard tone arm to the throat of the amplifier, which elements are of about the same diameter, is preferably relatively short, since this conduit acts as a connector with little or no amplification. For neatness of construction, it is preferred to provide the valve and knob near the center of the rectangular casting and the telephone receiver and tone arm at equal distances therefrom toward the opposite sides thereof. Accordingly, to provide the long passage for the radio conduit, the latter is made of reversely curved, generally ram's-horn shape, while the former is relatively straight.

In the extreme positions of the valve, it is desirable that the latter provide an effective opening as best shown in Figs. 3 and 4 with respect to the conduit of substantially the full diameter of said conduit, yet in each

of these extreme positions, the effective conduit is to be completely closed off from the other conduit. If the two conduits have equal diameters, which is preferably the 5 case at the point of discharge to the amplifier and were to merge in direct alignment with each other, it is apparent that the latter object could be attained, if at all, with difficulty where the diameter of the valve is kept 10 at a minimum. By my arrangement, the ram's-horn conduit communicates with the valve casing at an obtuse angle illustratively of about 135 degrees with respect to the conduit 24, the stop screw 38 registering with 15 peripheral groove 37 about the valve, limiting the rotation of the valve through a corresponding obtuse angle, so that effective lengths of arc of the valve provide the closure between the two conduits both in the 20 position shown in Fig. 3 and in that shown in Fig. 4, the effective length of closing arc of the valve at the front being considerably more than 90 degrees and at the back being about 45 degrees, in the specific embodiment 25 shown. In all intermediate settings of the valve, the communication between the radio conduit 25 and the phonograph conduit 24 is effectively prevented, while either of these conduits alone is in communication with the 30 amplifier. When the valve is in a position midway between the extremes shown in Figs. 3 and 4, it completely shuts off both passage-ways to the amplifier.

For supporting and rotating the valve, I 35 provide a valve stem 40 extended through the top of the casing 21 and suitably connected to a boss or lug 41 integral with the valve. The inner end of the valve stem may be buried at 42 to insure firm engagement with 40 the valve, or the valve and stem may be rigidly connected together in any other convenient or conventional manner. The end of the valve stem which projects beyond the housing 21 is secured within a tubular sleeve 43 rising from a circular plate 44. A set screw 45 may be used to make this connection. The sleeve 43 is, in turn, rigidly fixed to a 45 manually operable knob 46 which is used in rotating the valve.

The manner of attaching the knob to the sleeve is not important but I find it convenient to form the knob with an integral depending socket portion 47 within which the roughened exterior of the sleeve 43 engages. 50 The connection between the sleeve 43 and the socket 47 may be either a force fit or molded connection. Both the knob 46 and the socket 47 are slotted at 48 to accommodate and provide ready access to the set screw 45.

In order that the position of the valve 22 may be visibly indicated at all times, I provide a stationary dial member 49 associated 55 with a finger 50 (Fig. 5) the latter rigid with the valve. Preferably the stationary

dial member is fitted within a depression 51 on the top of the housing 21 and secured thereto by screws or similar devices 52.

To enhance the attractive appearance of the device and to facilitate operation of the 70 same, I prefer to cant or incline the valve housing 21 to approximately the angle shown in Fig. 2. Valve 22 is thus disposed at an angle to the vertical plane of the casting 15 and the upper outer surface of the housing 75 22 together with the dial and knob are inclined in the direction of the front of the phonograph. The manner of graduating the dial is arbitrary, but I prefer to use suitable indicia to designate the off or neutral center 80 position of the valve and to graduate the scale to indicate the extent to which the valve has been opened in either direction. These graduations are also associated with 85 suitable designations, as shown.

The construction shown in Figs. 1 to 6 being mounted as shown in the drawings, the operation for phonographic purposes, is performed in the usual manner. To modulate the volume, it is merely necessary to rotate the knob 46, so that pointer 50 moves along the scale divisions appearing at the right half of Fig. 5, whereby more or less of the valve 22 will be interposed across conduit 24. In any setting of the valve, it will be seen that the rotary valve is sufficiently tight to avoid rattling or setting up vibrations of its own and, moreover, avoids the leak or interference 90 which may attend the use of flat or disk or spring-actuated valves for this purpose. It will be noted that in all settings, the valve provides an effective seal with respect to the conduit 23 leading to the radio receiver, eliminating any dissipation or rattling by 95 sympathetic vibration in the receiver diaphragm.

For radio operation, the valve is turned to the position shown in Fig. 4, in which case, it 100 will be noted that the vibrations originating in the telephone diaphragm are amplified in the continuously diverging radio conduit 23, which conveys the vibrations in a regular continuous sweep into the throat of the amplifier. The valve 22 provides an effective seal of the 105 radio conduit with respect to the conduit 24 or the tone arm. By the present arrangement, the efficiency of the amplifying horn is not cut down as it would be where even minute leakage is permitted, near the small end 110 of the horn.

It will be seen that by rotation of the knob 6 so that the index 50 passes along the left-half of the scale divisions in Fig. 5, the volume emitted by the amplifier can be delicately 115 adjusted or controlled as desired, it being noted that for each setting of the valve, the tightness of the closure with respect to the tone arm is maintained. Thus, the volume 120 of sound is regulated without the need for 125 130

adjusting the electrical or magnetic controls of the receiving set in any way.

My apparatus provides a compact unit which can be easily applied to a phonograph 5 of otherwise ordinary design by merely providing a rectangular opening as in Fig. 1, instead of the usual circular opening. Hereinafter, I have described, however, an embodiment of the invention applicable without any 10 change whatsoever, to phonographs of construction now in use, in which the motorboard has a circular opening only for the mouth of the tone arm.

My radio conduit and receiver being rigidly 15 mounted upon the phonograph independently of the moving tone arm, not only dispenses with the need for substituting the telephone receiver for the sound box and vice versa, with corresponding inconvenience, 20 wear and rattle, but no added weight or drag is imposed on the tone arm, which would be likely to unduly wear out the grooves. By my invention, even if a telephone receiver of considerable weight is used, the operation of 25 the phonograph is not impaired and the life of the record is not shortened as compared to its use on an ordinary phonograph. Moreover, I provide highly efficient amplification for 30 radio purposes in that I avoid the leak near the throat of the amplifier which may occur 35 particularly at the swivel mount of the tone arm, where such tone arm serves to convey the vibrations from the telephone receiver to the amplifier throat, or at the radio inlet to the 40 amplifier, where the radio receiver delivers past a flap valve in the lateral wall of the 45 amplifier and near the throat thereof.

In certain of the claims I have defined the 45 amplifier wall as "continuous" meaning that it is devoid of any outlet or inlet anywhere 50 between the throat and the mouth of the amplifier.

In Fig. 7 of the drawings, I have shown a 55 combined tone arm and radio receiver unit, especially applicable to phonographs already in use, the motorboard of which has a circular aperture 62 for the mouth of a tone arm only. The neck of the amplifier 60 in such machines is secured directly below opening 60 62 to the motorboard 61. In this instance, I employ a casting 63 also preferably of generally rectangular shape, but supported upon the upper surface of the motorboard instead of being countersunk in an opening therein.

Casting 63 is formed with radio conduits 65 and phonograph conduit 64 of the same general shape as the conduits 23 and 24, and communicating respectively with the tone arm 66 and a telephone receiver 67. These 60 conduits are adapted to be selectively placed in communication with the amplifier 60 by turning a control valve 68 similar to the valve 21 and similarly controlled by an exterior knob 69 connected to the stem 70 of the valve. 65 The appearance of the selector unit may be

enhanced by forming the casting with a substantially uniform exterior sloping side wall portion 72 suitably ribbed and grooved to lend strength and beauty to the casting.

Receiver 67 may be placed in communication with the small end of the passage-way 65 in any suitable manner. Preferably a depending socket 73 of the reproducer encircles a boss 74 forming an extension of the passage-way 65. The mounting of the tone 75 arm is substantially the same as the mounting shown in Figs. 1 to 6, but the wide supporting end of the arm is shortened to compensate for the height of the casting 63 above the motorboard.

It will be understood that while in many cases, it is preferred to mount the tone arm at one side of the valve knob and the radio receiver at the opposite side of the valve knob, my invention is not limited to such arrangement, but the two conduits may extend at angles relative to each other. For instance, in a phonograph of the construction in which the tone arm is mounted at the corner of the motorboard, it would be preferred to apply the valve knob at the corner and the radio and phonograph conduits at right angles to each other, extending one generally along the rear and the other generally along the side wall of the phonograph cabinet. It will also be understood that the phonograph and the radio conduits may extend one in a plane lower than the other, both in the same general direction or at an angle relative to each other, the two conduits controlled, if desired, 90 from a single valve of length to extend across both said conduits.

Obviously, if desired, I could employ instead of the single control valve, separate valves for the radio and phonograph conduits, but the former construction is preferred.

In Fig. 8 is illustrated a further modified form of construction entirely concealed in the phonograph. In this instance, the motorboard 80 is formed with an opening 81 encircled by a socket member 82 which provides the usual swiveled mount for a tone arm 83, the arrangement of the tone arm above the opening being entirely conventional. A substantially globular valve casing 84 is screwed or otherwise secured to the underface of the motorboard and formed with openings 85-86 registering respectively with the opening 81 and with the neck 87 of the amplifier, the throat of the latter secured to the lower end of casing 84. Valve casing 84 is also formed with a lateral opening 88 registering with the enlarged end of a radio conduit 89 in a casting 90 secured thereagainst by a flange 94 and secured to the underface of the motorboard. The conduit 89 serves to place the valve casing in communication with a telephone receiver 91. Conduit 89 may be of the same general shape as the conduits 65 130

and 23 and the receiver 91 preferably carries a socket 92 having a threaded connection with a boss 93 at the small end of the conduit 89.

A rotatable valve member 95 is formed 5 with a diametrical passage-way 96 extending therethrough and adapted to connect the tone arm with the amplifier. A radial passage-way 97 disposed at right angles to the passage-way 96 cooperates with this passage-way 10 to establish communication between conduit 89 and the amplifier 87 when the valve is turned at right angles to the position shown in Fig. 8. The operating means for this valve is indicated merely in dotted lines as comprising a stem 98 and knob 99. For convenient operation of the valve, it is desirable that the stem 98 be extended through a side wall of the machine and operated from the exterior of the machine by the knob. The 15 receiver 91 instead of being concealed within the motor casing of the machine may be connected to the conduit 89 through the motor-board, as indicated in dotted lines in this figure.

20 While I have shown the invention applied in a construction embodying but two conduits leading to the amplifier throat, one from the phonograph reproducer and the other from the telephone reproducer, it will be understood that the invention could be carried forward to embody three or more conduits embodying a plurality of radio conduits, or a 25 plurality of phonograph conduits.

I claim:

30 1. In apparatus of the character described, in combination, a phonograph amplifier having a throat, a tone arm for communication with said throat, a fixed conduit of generally ram's-horn shape having its wider end delivering into said throat and adapted for 35 mounting a telephone receiver at its restricted end, said conduit having substantially sound-tight means extending lengthwise thereof to block communication with the tone arm.

40 2. The combination of a tone arm and a fixed amplifier of a pair of fixed conduits, one of which is adapted to connect the tone arm and amplifier and the other of which is adapted to connect a telephone receiver and the amplifier, and a common control means for 45 optionally placing either one of said conduits out of communication with the amplifier.

50 3. The combination which includes a tone arm and an amplifier, of a member formed with a plurality of passage-ways therein, one of which is adapted to connect the tone arm and the amplifier and the other of which is adapted to connect the amplifier with a telephone receiver, said last-mentioned passage-way being of generally ram's-horn shape and control means for optionally placing either of said passage-ways in communication with the amplifier.

55 4. The combination which includes a cas-

ing, a tone arm and an amplifier, of a unit mounted on top of the casing and formed with a pair of passage-ways therein, one of which is adapted to connect the tone arm and the amplifier and the other of which is adapted to connect a telephone receiver with the amplifier, said last mentioned passage-way being relatively long and of continuously increasing diameter toward its delivery end, and a common control means for 60 optionally placing either of said passage-ways in communication with the amplifier.

5. The combination set forth in claim 4 in which the control means when set for telephone operation, establishes a relatively 65 sound-tight connection from the telephone passage-way to the amplifier.

6. The combination which includes a casing, a tone arm and an amplifier, of a fixed unit mounted at the exterior of the casing and 70 formed with a pair of passage-ways therein, one of which is adapted to connect the tone arm and the amplifier and the other of which is adapted to connect a telephone receiver and the amplifier, and a valve manually operable 75 to place either of said passage-ways in communication with the amplifier, said valve in either setting affording an entrance to the throat of the amplifier of the full area of said throat.

7. The combination which includes a cabinet, a tone arm and an amplifier of a removable fixed unit mounted at the exterior of the cabinet, formed with a pair of passage-ways 80 therein, one of which is adapted to connect the tone arm and the amplifier, and the other of which is adapted to connect a telephone receiver and the amplifier, said last mentioned passage-way being relatively long and of continuously increasing diameter toward its 85 delivery end and a valve manually operable to place either of said passage-ways in communication with the amplifier.

8. The combination which includes a tone arm and an amplifier, a motorboard therebetween, of a removable unit fixed upon the top of said motor-board, formed with a pair of passage-ways therein, one of which is adapted to connect the tone arm and the amplifier and the other of which is adapted to connect a telephone receiver with the amplifier, and a cylindrical valve manually operable 90 to throttle the passage from the tone arm to the amplifier, for varying the volume, and in one position to cut off communication between the tone arm and the amplifier for operation of the telephone.

9. The combination which includes a motor-board, an amplifier therein, of a fixed unit attachable on top of and formed with a pair of passage-ways therein and mounting said tone arm, one of said passage-ways adapted to connect the tone arm and the amplifier and the other adapted to connect a telephone receiver and the amplifier, and means for op-

tionally placing either of said passage-ways in full or partially throttled communication with said amplifier.

10. The combination which includes a cabinet and an amplifier therein, of a unit attachable to the cabinet and formed with a pair of passage-ways therein, both having inlets above the cabinet, one of which is adapted to connect the tone arm and the amplifier and the other of which is adapted to connect a telephone receiver and the amplifier, said passage-ways uniting in a valve chamber in advance of their communication with the amplifier, and a common control valve in said 15 chamber.

11. The combination which includes a cabinet having a motorboard, an amplifier therein, of a unit attachable on top of said motorboard and formed with a pair of passage-ways therein, one of which is adapted to connect a tone arm and the amplifier, and the other of which is adapted to connect a telephone receiver to the amplifier, and a rotatable control member for optionally placing either of said passages in partially throttled or completely open communication with the 20 amplifier.

12. The combination which includes a cabinet and an amplifier therein, of a unit attachable thereto and formed with a pair of passage-ways therein, one of which is adapted to connect the tone arm and the amplifier and the other of which is adapted to connect a telephone receiver and the amplifier, a rotatable control member for variably throttled or completely open communication between the unit and the amplifier, a knob on the exterior of said unit for rotating said member, and indicating means associated with the knob, comprising a finger carried by the knob and a fixed dial coacting with the finger.

13. An article of manufacture comprising a casting having a pair of passage-ways therein leading from one face thereof and merging at the opposite side to connect at said merging part into the amplifier of a phonograph for operative relation of a tone arm and a telephone receiver mounted at the non-merging ends of the respective passage-ways, and a control valve member by which the cross-sectional area of the phonograph passage-way may be varied, said valve in one position closing the passage-way to the tone arm and establishing communication from the telephone receiver to the amplifier.

14. An article of manufacture comprising a casting having a pair of passage-ways therein adapted to connect the small end of the amplifier of a phonograph in operative relation with a tone arm and with a telephone receiver respectively, and a common control member for optionally connecting either passage to deliver into the small end of the amplifier, said control member comprising

a valve having limited rotary movement in the casting and constructed and arranged in manner such that when the tone arm is in communication with the amplifier, the tone receiver is sealed therefrom and vice 70 versa.

15. In a phonograph construction, in combination, a structure having a pair of passage-ways therein, for connection to the small end of the amplifier, a telephone receiver at the inlet end of one of said passage-ways, and a swivel structure carried by the inlet of the other said passage-way to mount a tone arm, said inlets both at the upper face of said structure.

16. In a phonograph construction, in combination, a structure having a pair of passage-ways therein, for connection to the throat of the amplifier, means at the end of one passage-way providing a swiveled mount 85 for a tone arm carried by said structure, and means at the end of the other passage-way providing a mount for a telephone receiver, said telephone receiver mount at the upper face of the structure.

17. In an apparatus of the character described, in combination, an amplifier, having a throat, a sound reproducer, a conduit connected to said sound reproducer, said conduit including a cylindrical valve with an open bottom communicating with said throat and having an opening in one side thereof adapted to establish communication between said sound reproducer and said amplifier throat.

18. In apparatus of the character described, in combination, an amplifier, a plurality of sound reproducers, separate conduits connecting each of said sound reproducers with the small end of said amplifier, 105 and a valve in advance of said small end controlling communication between said sound reproducers and said throat, said valve constructed and arranged to afford communication to the amplifier with not more than one 110 reproducer in each extreme or intermediate position thereof.

19. In apparatus of the character described, in combination, a selector unit to deliver to the small end of an amplifier, said 115 unit including a pair of conduit passages therein, delivering at an obtuse angle with respect to each other into a common valve casing communicating with the amplifier, a rotary valve therein to communicate with 120 either of said passages, and means limiting the rotation of said valve through an angle substantially equal to said obtuse angle, so that in all positions of said valve, communication between the two conduits is prevented. 125

20. The combination with a phonograph, including a motorboard having an opening therein and an amplifier registering with and directly connected to the underface of the motorboard about said opening, of a sepa- 130

- 10 rable structure supported upon the motorboard, and including a tone arm and a telephone receiver, said structure having a pair of passage-ways therein, connected respectively with the tone arm and the receiver, and both communicating with the amplifier, and a common control member for both passage-ways mounted in the structure directly above the opening in the motorboard.
- 15 21. In combination, a cabinet, a fixed amplifying horn therein, a phonograph tone arm, a telephonic speaker above the cabinet and having a fixed position relative to the horn, and means interposed between said phonograph tone arm and said horn on the one hand and between said telephonic speaker and said horn on the other hand, for selectively connecting either the tone arm or the telephonic speaker to deliver into the small 20 end of said amplifying horn.
- 25 22. In combination, a motorboard, an amplifying horn, a phonograph tone arm, a telephonic speaker and stationary means on top of the motorboard and interposed between said tone arm and amplifying horn on the one hand and between said telephonic speaker and amplifying horn on the other hand for selectively connecting either the one or the other to deliver into the small end of said 30 amplifying horn a wave front of the area of said small end.
- 35 23. In combination, a motorboard, an amplifying horn, a phonograph tone arm, a telephonic speaker, and means fixed on top of the motorboard and interposed between said tone arm and motorboard on the one

hand and between said telephonic speaker and motorboard on the other hand for selectively connecting either the one or the other with said horn.

24. In combination, a motorboard, an amplifying horn, a phonograph tone arm, a telephonic speaker and a unit on top of said motorboard and fixedly interposed between said tone arm and amplifying horn on the 45 one hand and between said telephonic speaker and amplifying horn on the other hand, said stationary unit being provided with means for selectively placing into acoustic communication either the tone arm or the telephonic 50 speaker to deliver into the small end of said amplifying horn.

25. In combination, an amplifying horn, a phonograph tone arm, a telephonic acoustic passage, and means interposed between said amplifying horn and said tone arm and passage, whereby the extent of acoustic communication between either the tone arm or the passage may be varied while communication between the tone arm and the acoustic 55 passage is at all times closed.

26. In combination, a stationary amplifying horn, a motorboard, a phonograph tone arm, a telephonic speaker, and means fixedly mounted on top of the motorboard and carrying said tone arm and said speaker for selectively connecting either the one or the other with said horn.

Signed at New York city in the county of New York and State of New York this 17th 70 day of May, A. D. 1924.

MAXIMILIAN WEIL.
